METHOD AND EQUIPMENT FOR FILLING OPEN MOUTHED RECEPTACLES
WITH COMMINUTED MATERIAL OR THE LIKE

Filed July 11, 1962

FIG. 1

1

3,195,786
**METHOD AND EQUIPMENT FOR FILLING OPEN
 MOUTHED RECEPPILES WITH COMMINUTED
 MATERIAL OR THE LIKE**

Clarence W. Vogt, Box 232, Westport, Conn.
 Filed July 11, 1962, Ser. No. 209,025
 12 Claims. (Cl. 222—394)

This invention relates to the art of packaging, and more particularly to the filling of open mouthed receptacles or containers with predetermined weights of finely divided or comminuted material and/or mixtures which may be in the form of powder, grains, granules, particles and the like, flowable under gaseous pressure greater or less than atmospheric.

As conducive to an understanding of the invention, it is noted that where material of the above type, all of which may hereinafter be referred to in the specification and claims for convenience, as comminuted material, is charged into open mouthed containers or cavities such as bags or bottles, by sifting or discharging it through a tube, the operation is extremely time-consuming, especially where large numbers of containers are to be filled. In addition, due to the large amounts of air entrained with some materials, the latter is not firmly packed or compacted into the container with the result that a given volume of the material has relatively little weight and in addition, due to indeterminate quantities of air that remain in the material, the weight of a given volume varies from container to container.

Where, in an attempt to speed up the filling operation, gas under pressure is applied to a magazine containing such material to force the latter through the outlet of the magazine into the container to be filled, it has been found in many cases, due to the inertia of the material, the gas under pressure will channel through the material and through the outlet of the magazine into the container so that such container will only fill partially with the material.

Furthermore, it is to be noted that with many materials, the outlet of the magazine must be provided with a valve that will close to prevent discharge of material during successive filling operations and also sifting of material from the magazine when the latter is initially loaded.

Where the valve is of the type that has a fixed member and a movable member to effect opening and closing thereof, the comminuted material is likely to clog between such members with the result that the valve becomes difficult to operate and often becomes inoperative and must be cleaned. This requires disassembly of the equipment which is time-consuming and results in loss of production.

It is accordingly among the objects of the invention to provide a relatively simple method and equipment for expeditiously filling open mouthed containers with comminuted material at a relatively high rate of speed with assurance that successive containers in a given run of material will be charged with substantially equal weights of such material and without likelihood of jamming of the valve utilized between the magazine and the container so that disassembly of the equipment for cleaning of the valve is eliminated.

According to one aspect of the invention, a magazine is provided having an outlet controlled by a flexible valve member which automatically opens when flow through the valve member is desired, and will automatically restrain further flow between the charging cycles.

The equipment has means to apply a vacuum to the outlet side of the flexible valve to cause the latter to permit flow therethrough and also to cause the material in the magazine to flow through the open valve into a container immediately therebelow and in sealing engage-

2

ment with the outlet end of the magazine and encompassing said valve.

According to another aspect of the invention, means are provided to apply a source of gas under superatmospheric pressure to the contents of the magazine immediately after such contents have begun to flow through the open valve by the application of such vacuum, thereby assisting such movement of the contents and increasing its flow velocity to provide a charge of material in the container that is in compacted form and of relatively heavy weight for a given volume.

In the accompanying drawings in which is shown one or more of various possible embodiments of the several features of the invention:

15 FIG. 1 is a longitudinal sectional view of the filling equipment according to one embodiment of the invention.

FIG. 2 is an exploded detail plan view on a larger scale of the valve portion of the equipment of FIG. 1,

20 FIG. 3 is a view taken along line 3—3 of FIG. 1,
 FIG. 4 is a detail view similar to FIG. 2 of the valve portion assembled,

25 FIG. 5 is a detail view of another embodiment of the valve member showing in broken lines the valve flaps in spaced position, and

FIG. 6 is a perspective view showing the valve member and liner as separate elements.

Referring now to the drawings, the equipment desirably comprises a cylindrical casing 11 having an annular flange at its upper end which extends laterally inward and outward of the casing 11 as at 12 and 13.

30 Associated with the casing 11 is a gas chamber which desirably comprises a casing 14 having opposed walls 15 and 16 and an enlarged portion 17 defining a gas reservoir. The walls 15 and 16 have vertically aligned openings 18 and 19, and the wall 15 has an upstanding rim 21 coaxial with opening 18 and of inner diameter greater than that of opening 18 to define an annular shoulder 22.

The rim 21 and the casing 11 are secured together as 40 by screws 23; the inner surface of rim 21; the opposed wall 11' of casing 11; the undersurface of flange portion 13 and the shoulder 22 defining an annular chamber 24.

Extending through the opening 19 in wall 16 is an 45 elongated sleeve 28 of inner diameter slightly less than that of casing 11. The sleeve 28 adjacent its lower end which has a beveled annular flange 29, has an annular flange 31 which is secured to the undersurface of wall 16 as by screws 32. The length of the sleeve 28 is such that when so mounted, its upper end 33, which is beveled 50 as at 34 on its inner surface, will extend slightly into opening 18, being vertically spaced from the lower end 35 of casing 11 to define an annular port 36, the outer diameter of sleeve 28 being less than the inner diameter of opening 18 to define an annular gas inlet port 37.

55 As the diameter of opening 18 is greater than the outer diameter of the cylindrical portion 11' of casing 11, an annular passageway is provided, to accommodate the annular skirt 39 of an annular piston 41 slidably mounted in chamber 24, the portion of chamber 24 beneath the piston being vented as at 41'. The lower end of skirt 39 has an inwardly extending annular flange 42 which is movable in port 36, between the opposed ends 33 and 35 of the sleeve 28 and the casing 11 respectively and defines a valve member.

To provide an effective seal for the piston 41, annular seals 43, 44 are provided in its inner and outer peripheries and the skirt 39 is provided with an external annular seal 45 which engages the wall surface of opening 70 18. In addition, the upper end 33 of sleeve 28 has an annular seal 46 against which the valve member or flange 42 may abut.

Desirably, the dimensions of the piston 41, the flange 42 and the port 36 are such that when the flange 42 is in its uppermost position against the end 35 of casing 11, the top surface of the piston 41 will be spaced from the undersurface of flange portion 13 as shown.

Secured as by screws 51 to the flange portion 13 is a cover plate 52 which has a beveled central port 53 aligned with the casing 11. The cover plate 52 has an elongated recess 54 in its undersurface which in conjunction with the flange of casing 11 defines a channel in which a plate 55 having an aperture 56 is slidably mounted to open and close the port 53 as desired. An annular gasket 57 is provided in the flange portion of the casing 11 coaxial with the port 53 to provide a seal with respect to plate 55 and port 53. A hopper 58 is mounted on the top surface of the cover plate 52.

Positioned in the casing 11 and sleeve 28 and extending coaxially therewith is a cylindrical filter liner or sleeve 61 which is laterally spaced from the casing 11 and the sleeve 28 to define an annular chamber 62. To this end, the inner flange portion 12 has a reduced diameter portion 63 on its undersurface which encompasses the upper portion of liner 61. The lower end of the liner has an outwardly extending annular flange 64 which seats in an annular recess 65 in the lower end of the sleeve 28.

The liner 61 is of gas permeable material such as sintered metal, sintered polyethylene, paper impregnated with epoxy or other suitable resins, porous "Teflon" and "Kel-F."

The liner 61 is releasably held in position as by a cup-shaped retainer 66 which has an annular top surface 67 with an upstanding peripheral rim 68 that encompasses the lower end 29 of sleeve 28, the beveled portion of end 29 being engaged by inclined screws 69 through rim 68 releasably to mount the retainer 66.

The inner surface 72 of the retainer tapers inwardly to a port in the lower end thereof, said port being axially aligned with the liner 61.

The retainer 66 in its undersurface, coaxial with said port has an annular recess 74, the upper surface of which has an annular groove 75 and the outer surface of which is threaded as at 76.

Positioned in the retainer, which defines the lower end of the magazine, is a liner 81 of resilient material such as rubber which may be natural or synthetic. The liner is substantially frusto-conical as shown, having a tapering body portion 82, the slope of which is greater than that of the inner surface 72 of the retainer. The larger diameter end 83 of the liner has an outwardly extending annular flange 84 which is positioned on the top surface 67 of the retainer member and which will be clamped in place when the screws 69 are tightened to provide a seal.

The lower reduced diameter portion end of the liner 81 has a transverse wall portion 85 extending beyond the bottom surface of the retainer as is clearly shown in FIG. 4. The transverse wall portion 85 has cross slits 86 therethrough, preferably extending at right angles to each other, said cross slits also extending through the portion of the body portion or side wall 82 of the liner adjacent the transverse portion 85 as at 87, as is clearly shown in FIG. 4. The cross slits thus illustratively define four closure flaps 88 which have their root ends at the outer periphery of the wall portion 85 and which, by reason of the resilience of the liner, are normally in closed position as is clearly shown in FIG. 4, to define a valve 90.

It is noted that each of the closure flaps 88 has its root end along a curved line, that is a segment of the extreme lower portion of the side wall 82 of the liner. It is well known that the resistance to bending of a curved member generally along an arc thereof is much greater than the bending of a planar member. Further, when a resilient curved member is bent or folded so that a portion thereof must temporarily define a straight line, much energy is stored within the member constantly urging the member back to its cross section with the result that the closure

flaps 88 are more strongly urged towards their normal closed positions of FIG. 4 than that closing action due to the resiliency of the material from which the liner 81 is formed.

5 The outer surface of the side wall 82 of the liner has an annular laterally extending flange 89 with an annular groove 91 in the top surface thereof defining a peripheral ridge 93 adapted to be positioned in the annular groove 75 in the recess 74 in the retainer.

10 Means are provided securely to clamp the lower end of the liner 81 in position.

To this end, as is clearly shown in FIGS. 1 and 2 and 15 4, a rigid disc or plate 94 is provided which has an annular rim 100 on its outer periphery defining a recess and a large central opening 95 therethrough with a plurality of perforations 96 through the portion thereof outwardly of the central opening 95 and inwardly of the rim 100. The disc or plate 94 is positioned against the undersurface of the retainer 66 as is clearly shown in FIG. 1. Positioned in the recess of the disc 94 is a disc 101 of porous material which may be of impregnated paper, if desired, or of sintered polyethylene or the like. The disc 101 also has a central opening 102 therethrough aligned with the opening 95 in the plate 94.

20 To retain the parts together, a clamp plate 77 is provided which has a central opening 78 having a curved inner periphery 79. An annular resilient gasket 80 is positioned between the clamp plate 77 and the plate 94, and the parts are secured to the undersurface of the retainer 66 as by recessed screws 98. It is to be noted that the gasket 80 is of width such that its inner periphery will extend beyond the outer periphery of disc 101 to form a seal. In addition, a locking ring 103 is provided which, as is clearly shown in FIG. 2, has an inwardly extending annular flange 104 and an outwardly extending annular flange 105, the outer periphery of the locking ring being threaded as at 106 so that it may coact with the threads 76 in recess 74.

25 The locking ring is so conformed that it will fit through the aligned openings 95 and 102 in plate 94 and disc 101 and engage the threads 76, the ring being rotated as by means of a spanner wrench applied to the openings 107 in flange 103. When the locking ring is tightened, the top surface 103 of flange 103 will react against the bottom surface of annular flange 89 to force the ridge 93 of the latter into annular groove 75 in recess 74 and the flange 105 will press against the undersurface of the margin of the opening 102 in disc 101 thereby retaining the assembly in securely clamped position. Desirably as shown, the inner periphery 111 of the flange 104 is rounded to prevent cutting of the outer surface of the side wall 82 of the liner 81.

30 The undersurface of the retaining member 66 has an annular groove 115 encompassing the port thereof and 35 in communication with a port 116 leading into the annular groove 115.

40 By reason of the difference in the angle of taper of the wall 72 of the retainer 66 and the wall 82 of the liner 81, a chamber 117 will be defined therebetween, 45 which chamber is in communication with the exterior of the unit through port 118, the latter being connected to a valve V-3, which has two ports Y-1, Y-2 either of which may be connected to port 118.

45 By alternately subjecting the interior and exterior surfaces of the wall 82 of liner 81 with different pressures, through ports Y-1, Y-2, the liner will alternately move inwardly and outwardly loosening the material remaining in the liner after the filling operation.

50 This is especially useful at the end of a run so that 55 all residual material can readily be discharged from the liner and valve.

55 Means are provided to actuate the piston 41 and valve member 42 and to relieve the gas under pressure in liner 61 at the end of the filling cycle, which is necessary when the filling is accomplished at least in part by the use of

pressure greater than atmosphere in the manner herein-after described. To this end, as shown, passageways 121 and 122 are provided in the flanged portion 13 leading respectively from the chamber 24' between the top surface of piston 41 and flange 13 of casing 11 to a port 123 and from the annular chamber 62 between the casing 11 and the liner 61 to a port 124.

With the slide plate 55 in open position and the hopper 58 charged with the comminuted material to be packaged, which will flow into the liner 61, which defines a magazine, and into liner 81 to fill such liner, a container R is positioned in a holder H on a support S beneath the retainer member 66. As illustratively shown, the diameter of the container R is such that its mouth 125 may press against the undersurface of the resilient gasket 80, the container being centered by the curved inner periphery 79 of clamp plate 77.

To control the operation of the equipment, a valve V-1 is provided which has a port P-1 connected to port 124 and a port P-2 connected to port 123. The valve has a pressure inlet port P-3 and an exhaust port P-4. In the "blow" position of the valve V-1 as shown, ports P-2 and P-4 are connected and in the "normal" position of the valve, ports P-2 and P-3 are connected and ports P-1 and P-4 are connected, the port P-4 leading to atmosphere.

The port 116 of the retainer is also connected to a second valve V-2. This valve has a port X-1 which is connected to port 116 and two additional ports X-2 and X-3 connected respectively to a source of gas under pressure and to a vacuum source. The valve is so designed that normally all of the ports may be closed as shown. In one position of the valve, the ports X-1 and X-2 may be connected and in another position of the valve, ports X-1 and X-3 may be connected for the purpose herein-after to be described.

With the valve V-1 in the "normal" position, gas under pressure is applied through ports P-3, P-2 to port 123, the ports P-1 and P-4 also being connected, so that port 124 is connected to atmosphere to exhaust the annular chamber 62.

The valves V-1, V-2, V-3 preferably are of the solenoid operated spool type for fast action.

As the upper surface area of the piston 41 exposed to the air pressure in chamber 24' from port 123 is greater than the undersurface area of the valve member 42 exposed to the gas pressure in reservoir 17 which is charged to the same pressure as that applied to port P-3, the piston 41 will be normally retained in its downward position so that the valve member 42 engages the gasket 46 to provide a seal between the reservoir 17 and the annular chamber 62.

To operate the unit, according to one illustrative embodiment of the invention, the slide plate 55 is closed after the liners 61 and 81 are filled with material. By reason of the resilience of the material from which the liner is made, the flaps 83 of the valve 90 will be in closed position with their adjacent edges in engagement as shown, restraining flow of the material from the magazine liners 61 and 81.

Thereupon, the valve V-2 is actuated to connect the ports X-1 and X-3. Switch SW-1 is then closed so that solenoid valve SV will substantially instantaneously apply vacuum through connected ports X-1, X-3 to port 116 of the retainer 66 and through the openings 96 and porous disc 191, such vacuum will be applied to the interior of the container R. As a result of such vacuum, gas in the container will immediately be exhausted therefrom and in addition, due to the vacuum created, the flexible flaps 83 of the valve 90 of the liner 81 will move downwardly and outwardly pivoting about their curved root ends, thereby opening the valve so that the vacuum applied will draw material from the magazine and start flow of such material into the container. As a result of such vacuum, the side wall 82 of the flexible liner 81

would tend to bow inwardly and restrict the passageway.

However, the valve V-3 at this time, illustratively is in position to connect port 118 to port Y-1 which is connected to a source of vacuum to overcome the inward movement of the liner.

At this time valve V-1 is in "normal" position so that chamber 62 is connected to atmosphere through ports P-1, P-4. This permits unimpeded suction action. Substantially immediately after such vacuum is applied through valve V-2, the valve V-1 is moved to the "blow" position and valve V-3 is moved to connect port 118 to port Y-2 which is connected to a source of pressure.

As a result, ports P-2 and P-4 will be connected to cut off the gas under pressure to port 123 and chamber 24' and vent said chamber to atmosphere and port 124 will be closed. Consequently, the greater pressure against the valve member 42 due to the gas pressure in reservoir 17 will rapidly lift the valve member 42, to provide communication from reservoir 17 and port 37 through port 36 to the annular chamber 62. This surge of gas under pressure will flow through the porous liner 61 to react against the top and sides of the column of material in the liner, forcing such material downwardly and through the open valve flaps 83 into the container at relatively high velocity so that the container will be filled with the comminuted material in compacted form. As the liner 81 has been retained in substantially its normal position by reason of the pressure applied to port 118, flow of material through the liner is unimpeded.

As a substantial portion of the air in the container R was exhausted when the vacuum was initially applied thereto and as almost all of the entrained air forced into the container R will be immediately removed therefrom by the continuation of such vacuum, it is apparent that the compaction will be to a relatively great extent so that a relatively heavy weight of material may be charged into a container of a given volume.

Since the material in the magazine has started to move by the application of the vacuum, the subsequent application of the gas under pressure will not result in funneling of gas through the material which would interfere with proper filling of the container, but the material will flow readily through the open valve flaps 83 into the container.

It is to be noted that the vacuum is applied extremely rapidly by reason of the rapid opening of solenoid valve SV. This insures dependable starting movement of the material through the valve 90 which will open substantially simultaneously with the application of the vacuum to port 116.

After the container R is filled, which is almost instantaneously, the valve V-1 is actuated to "normal" position, which will again connect the source of gas under pressure to port 123 which will reclose the valve member 42, and vent 41', permitting downward movement of the valve member 42, and which will connect port 124 through ports P-1, P-4 of valve V-1 to atmosphere to release the gas in the liner 61, the latter, by reason of its porosity, permitting passage of gas therethrough, but restraining escape of the comminuted material. At substantially the same time, the valve V-2 is moved to the closed position shown. This will cut off the vacuum and switch SW-1 is then opened.

It is to be noted that the filling continues until such time as the receptacle is filled and the material charged into the receptacle backs up against the valve 90 preventing additional material from flowing therethrough. This is irrespective of any pressure or vacuum that may be applied after the receptacle has been filled. After the release of the pressure and vacuum, the valve flaps 83 will tend to move inwardly by reason of their natural resilience and because the bending of the fold line for each valve flap is along a curved surface. This tendency of the valve flaps 83 to move toward closed position, as shown in broken lines in FIG. 5, serves gently to retain

between the valve flaps the material which has not passed through the valve 90 so as to prevent leakage or filtering of the material through the valve 90 at the time the filled receptacle is being removed so that no additional material will be delivered to the receptacle after the termination of the filling operation. This provides fine control of the volume and weight of material charged into the receptacle.

Thereupon, the support S is moved downwardly a very small amount, in the first instance, and the valve V-2 is moved to position to connect ports X-1, X-2 so that a relatively slight amount of gas under pressure which may be but slightly above atmospheric will be applied to port 116 to pass through the perforations 95 in disc 94 and through the porous disc 101 to clean any material adhering thereto so that the equipment will be ready for the next cycle. The valve V-2 is then moved to closed position and then the support is moved downwardly for removal of the container and the operation then can be repeated.

In FIG. 5 there is illustrated a liner 81' which is provided at the lower end thereof with a modified form of valve 90' which generally corresponds to the valve at the bottom of the liner 81 and specifically illustrated in FIGS. 2 and 4. The valve 90' differs from the valve of FIGS. 2 and 4 in that it is of an inverted conical configuration and is formed of a plurality of closure flaps 131 which are separated by means of cross slits 132. It is to be understood that the cross section of each of the closure flaps 131 is arcuate with the result that any force exerted on the closure flaps 131 to move the same from the solid line positions of FIG. 5 to the dotted line positions of the same figure will require the bending or folding of each closure flap 131 along a line disposed around an arcuate surface with the result that the resistance of each closure flap 131 to movement to a valve opening position is greater than that of the normal resistance of the material of the liner 81' to bending. In addition, when each closure flap 131 is bent from its normal solid line position of FIG. 5 to the dotted line position of the same figure, energy is stored within the closure flap, due to the resiliency of the material from which it is formed, urging the closure flap to its valve closing position.

It will be readily apparent that when any upward pressure is directed against the valve 90', the effect of this pressure on the closure flaps 131 merely serves to urge the closure flaps together more tightly due to the conical arrangement of the valve flaps and the fact that each flap serves to support the other as the valve flaps are forced together. Such an upward pressure may occur due to the sudden release of the blow pressure which creates somewhat of a suction effect on the magazine above the valve 90' and unless the valve 90' properly operates, the suction effect would permit some of the material deposited in the receptacle to be drawn back into the magazine.

It is to be understood that it is not necessary for either of the two valves 90, 90' to be integrally connected to the associated liner 81 or 81'. Thus, the valve may be formed separate from the liner and the valve may be provided with an annular flange 141 which may be formed complementary to the flange 89a of the liner. This construction is shown in FIG. 6 in which parts corresponding to those in FIG. 5 have the same reference numerals.

By reason of the flexible valve members 90, 90' employed, sifting of material from the magazine when it is initially charged and during successive filling operations is precluded.

As the valve members 90, 90' have no mechanical parts which are in engagement with each other and between which material may accumulate, there is no possibility of jamming of the valve and it will operate for long periods without derangement.

It is within the scope of the invention to utilize the equipment with merely the suction or vacuum action and without applying any blow pressure.

In such case the valve V-1 is retained in its "normal" position so that no gas under pressure can enter into the magazine and the slide plate 55 is maintained in open position so that its opening 56 is aligned with the hopper and the magazine.

Thereupon, the filling action may be performed by merely applying the vacuum to the port 116 so that it is the vacuum alone that affects the filling action.

The use of vacuum alone to effect the filling action does not generally provide the degree of compaction that will be afforded by the use of vacuum and blow pressure, but in many cases it is sufficient to accomplish the desired filling action.

As the surface area of the porous portion of the disc 101 exposed in the container R is relatively great, even though when the vacuum is applied to port 116, some of the material drawn into the container from the magazine may tend to adhere to the undersurface of the porous disc 101, sufficient area is provided so that the container R will fill completely before there is any complete blocking of the surface of the porous disc 101 in communication with the annular recess 115 thereby insuring dependable filling action.

In the illustrative embodiments herein, the cross sectional area of the filter liner 61 is approximately one square inch and the cross sectional area of each of the valves 90, 90' when full open is approximately .027 square inch. As a result of the relatively small valve opening, as compared to the diameter of the liner 61, material passing therethrough do so at relatively high velocity.

The high velocities obtainable by using the pressure differentials in connection with the equipment and methods disclosed herein result in portions of extremely accurate weights of air entrained flowable solids.

As many changes could be made in the above method and equipment and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. Equipment of the character described comprising a magazine for comminuted material having an outlet port at one end, a valve in said outlet port, said valve comprising a flexible member extending across said outlet port and having a plurality of slits therethrough defining valve flaps normally urged to closed positions, and means to apply gas under pressure deviating from atmospheric pressure in direction to react against said valve flaps to cause the latter to open, thereby permitting flow of material through the open valve from the magazine, the lower end of the magazine having a substantially tapering wall surface having said outlet port at its smaller end, a liner of resilient deformable material positioned in the lower end of said magazine, said liner having a tapering side wall being spaced from the tapering wall surface of the lower portion of the magazine to define a chamber therebetween, and means to apply gas under pressure deviating from atmospheric into said chamber to react against the side wall of said liner.

2. The combination set forth in claim 1 in which said means for supplying the gas under pressure supplies the gas at a pressure less than atmospheric and the gas is applied downstream of said valve flaps to react against the valve flaps to move the latter to open position.

3. As an article of manufacture a substantially frustoconical member of resilient deformable material having a transverse wall at the smaller diameter end thereof, said wall having a plurality of slits therethrough defining clo-

sure flaps, said flaps forming a valve and normally being in position with adjacent edges in engagement to effect closure of said valve, the portion of said frusto-conical member adjacent said transverse wall having a plurality of slits extending longitudinally thereof and in communication respectively with the slits in the transverse wall.

4. The article set forth in claim 3 in which the larger diameter end of said frusto-conical member has an outwardly extending annular flange formed integral therewith.

5. As an article of manufacture, a tubular liner of resilient deformable material and having a downwardly converging upstanding wall portion terminating in a lower end of reduced cross section as compared to the upper end thereof, a transverse wall at said lower end, a mounting flange extending radially outwardly from said liner at said transverse wall, said transverse wall being divided into a plurality of closure flaps having edges and with said closure flaps combining to define a valve, and said closure flaps being resiliently urged to a normal position wherein adjacent ones of said edges are in substantially contiguous relation to effect closure of said valve.

6. Equipment for delivering flowable solid material under the influence of differential gaseous pressure, comprising a magazine having a material delivering opening, said magazine having a lower portion thereof defined by a downwardly tapering liner of resilient deformable material, said liner having a lower end of reduced cross section as compared to the upper end thereof, a housing surrounding said liner in at least partially spaced relation thereto, a transverse wall at said lower end, said transverse wall being divided into a plurality of closure flaps having edges and with said closure flaps combining to define a valve, and said closure flaps being resiliently urged to a normal position wherein adjacent ones of said edges are in substantially contiguous relation to effect closure of said valve, means for applying a differential gaseous pressure to material within said magazine for forcing material through said valve and effecting the opening thereof, and means for alternately applying different gaseous pressure into the space between said housing and said liner exteriorly on said liner for alternately moving said liner inwardly and outwardly and loosening material within said liner at the termination of a material dispensing operation.

7. Equipment for delivering flowable solid material under the influence of differential gaseous pressure, comprising a magazine having a material delivering opening, said magazine having a lower portion thereof defined by a downwardly tapering liner of resilient deformable material, said liner having a lower end of reduced cross section as compared to the upper end thereof, a housing surrounding said liner in at least partially spaced relation thereto, a transverse wall at said lower end, said transverse wall being divided into a plurality of closure flaps having edges and with said closure flaps combining to define a valve, and said closure flaps being resiliently urged to a normal position wherein adjacent ones of said edges are in substantially contiguous relation to effect closure of said valve, means for applying a differential gaseous pressure to material within said magazine for forcing material through said valve and effecting the opening thereof, the differential gaseous pressure applying means being downstream of said valve and of the sub-atmospheric type normally directing an inward pressure on the interior of said liner tending to restrict flow therethrough, and means for applying a balancing sub-atmospheric pressure externally of said liner in the space between said housing and said liner during the application of the first-mentioned sub-atmospheric pressure to prevent the undesired inward deflection of said liner.

8. Equipment for delivering flowable solids under the influence of differential gaseous pressure, comprising a magazine having a discharge end, a hollow extension releasably clamped to said magazine at said discharge end

- a resilient liner within said hollow extension, said liner having a discharge opening remote from said magazine and a flow control valve normally closing said discharge opening, said liner having outwardly directed mounting flanges at the opposite ends thereof, one of said mounting flanges being clamped between said extension and said magazine, and a clamp member releasably carried by said extension clamping the other of said flanges to said extension.
- 5 9. The equipment of claim 8 wherein said liner and said extension are of configurations to define a space with said housing surrounding said liner, and means are connected to said extension for varying the pressure within said housing to control the shape of said liner.
- 10 10. The equipment of claim 8 wherein said extension has a vent passage therethrough with one end of said vent passage having an entrance opening through an end of said extension remote from said magazine, and a filter member covering said entrance opening, said filter member being secured in place by said clamp member.
- 15 11. As an article of manufacture, a substantially frusto-conical member of resilient deformable material, flanged adjacent both its upper and lower ends for maintaining said ends in spaced relationship, and having a transverse wall at the smaller, lower diameter thereof, said wall having a plurality of slits therethrough defining closure flaps, said flaps forming a valve normally being in position with adjacent edges in engagement to effect closure of said valve.
- 20 12. Equipment of the character described comprising a magazine for comminuted material having an outlet port at one end, a valve in said outlet port, said valve comprising a flexible member extending across said outlet port and having a plurality of slits therethrough defining valve flaps normally urged to closed positions, said flexible member being of a regular geometrical configuration generatable by pivoting a straight line about an axis, and means to apply gas under pressure deviating from atmospheric pressure in a direction to act against said valve flaps to cause the latter to open, thereby permitting flow of material through the open valve from the magazine, said means for applying gas under pressure supplying the gas at a pressure less than atmospheric pressure downstream of said valve flaps to react against said valve flaps to move the latter to open position, and said means for applying gas under pressure also supplying gas under superatmospheric pressure to the contents of the magazine upstream of said valve flaps to react against said valve flaps, whereby the material in the magazine will react against the valve flaps to open the latter for discharge of such material from the magazine.
